UNITED STATES PATENT OFFICE.

HENRY F. ALEXIS, OF FISH LAKE TOWNSHIP, CHISAGO COUNTY, MINNESOTA.

DESIGN FOR A BACK COMB.

51,542.

Specification for Design.

Patented Dec. 11, 1917.

Application filed September 28, 1917. Serial No. 193,857. Term of patent 3½ years.

To all whom it may concern:

Be it known that I, HENRY F. ALEXIS, a citizen of the United States, residing at town of Fish Lake, in the county of Chisago and State of Minnesota, have invented a new, original, and ornamental Design for Back Combs, of which the following is a specification, reference being had to the accompanying drawing, forming part thereof.

Fig. 2 is a side elevation.

I claim:

The ornamental design for a back comb, as shown.

HENRY F. ALEXIS.
